UNITED STATES PATENT OFFICE.

EDWARD G. GERMER, OF ERIE, PENNSYLVANIA, ASSIGNOR TO GERMER STOVE COMPANY, OF ERIE, PENNSYLVANIA, A CORPORATION OF PENNSYLVANIA.

DESIGN FOR A GAS-STOVE.

49,266.

Specification for Design.

Patented June 27, 1916.

Application filed April 26, 1915. Serial No. 24,159. Term of patent 14 years.

To all whom it may concern:

Be it known that I, EDWARD G. GERMER, a citizen of the United States, residing at Erie, in the county of Erie and State of Pennsylvania, have invented a new, original, and ornamental Design for a Gas-Stove, of which the following is a specification, reference being had to the accompanying drawing, forming a part thereof.

The figure is a perspective view of the stove showing my new design.

In this stove the fire face comprises a depressed frame and pellucid strips extending

vertically across the rear face of the frame and projecting outwardly from said rear face with a curved surface having a vertical axis, the rear face of the frame being on a plane relatively to the strips intersecting the curve formed by the strips continued.

I claim:

The ornamental design for a gas stove as shown and described.

EDWARD G. GERMER.
